No. 36,860.

Patented March 29, 1904.

UNITED STATES PATENT OFFICE.

ALFRED H. HUMPHREY, OF KALAMAZOO, MICHIGAN.

DESIGN FOR A BASE FOR GAS-LAMPS.

SPECIFICATION forming part of Design No. 36,860, dated March 29, 1904.

Application filed December 9, 1901. Serial No. 85,282. Term of patent 7 years.

To all whom it may concern:

Be it known that I, ALFRED H. HUMPHREY, a citizen of the United States, residing at the city of Kalamazoo, in the county of Kalamazoo and State of Michigan, have invented a new, original, and ornamental Design for a Base for Gas-Lamps, of which the following is a specification.

My new, original, and ornamental design for a base for gas-lamps is shown in the accompanying drawings, in which—

Figure 1 is a side elevation view, and Fig. 2 is a plan view thereof.

What I claim as new, and desire to secure by Letters Patent, is—

The ornmental design for a base for gas-lamps substantially as shown.

ALFRED H. HUMPHREY. [L. s.]
